US00D578650S

(12) **United States Design Patent**
Adams

(10) **Patent No.:** **US D578,650 S**
(45) **Date of Patent:** **** Oct. 14, 2008**

(54) **POSITIVE AIRWAY PRESSURE APPARATUS**

(76) Inventor: **Phillip M. Adams**, 313 Pleasant Summit Dr., Henderson, NV (US) 89012

(**) Term: **14 Years**

(21) Appl. No.: **29/298,771**

(22) Filed: **Dec. 12, 2007**

Related U.S. Application Data

(63) Continuation-in-part of application No. 11/856,568, filed on Sep. 17, 2007.

(51) **LOC (8) Cl.** **24-04**

(52) **U.S. Cl.** **D24/164**

(58) **Field of Classification Search** **D24/109, D24/110, 164, 185, 186; D23/355; D13/112, D13/116; D3/201, 203.1, 203.2, 203.6, 205; 128/204.18, 204.21, 204.22, 204.23, 205.15, 128/205.23; 55/356, 357**

See application file for complete search history.

CLAIM

The ornamental design for a positive airway pressure apparatus, as shown and described.

DESCRIPTION

FIG. 1 is a perspective view of a positive airway pressure apparatus, in accordance with my new design, having a lid in an open position;

FIG. 2 is a left side elevation view of the design of FIG. 1;

FIG. 3 is a right side elevation view of the design of FIG. 1;

FIG. 4 is a rear elevation view of the design of FIG. 1;

FIG. 5 is a front elevation view of the design of FIG. 1;

FIG. 6 is a top plan view of the design of FIG. 1;

FIG. 7 is a bottom plan view of the design of FIG. 1; and,

FIG. 8 is a perspective view of the design of FIG. 1 having the lid in a closed position.
